SWITCH INDEX MECHANISM

Kennard Newman, Indianapolis, Ind., assignor to
 P. R. Mallory & Co., Inc., Indianapolis, Ind., a
 corporation of Delaware

Application November 20, 1937, Serial No. 175,612

1 Claim. (Cl. 74—97)

This invention relates to electric switches and more particularly to indexing means therefor.

An object of the invention is to improve the indexing means for electric switches.

Other objects of the invention will be apparent from the following description and accompanying drawing taken in connection with the appended claim.

The invention comprises the features of construction, combination of elements, arrangement of parts, and methods of manufacture and operation referred to above or which will be brought out and exemplified in the disclosure hereinafter set forth, including the illustrations in the drawings.

In the drawing:

Figure 1 is a perspective view of a portion of an electric switch showing the index means therefor;

20 Figure 2 is a top view of the index mechanism; Figure 3 is a section on the line 3—3 of Figure 2;

Figure 4 shows a modified means for mounting part of the index structure; and

25 Figure 5 is a section on the line 5—5 of Figure 4.

According to the invention a switch index means is provided which is suitable for rotary-type multi-position switches. The index mechanism is particularly well adapted for use in switches of the type shown and described in H. Hall application Serial No. 93,809, filed August 1, 1936. The mechanism is also adapted for use with other types of switches.

30 While a preferred embodiment of the invention is described herein, it is contemplated that considerable variation may be made in the method of procedure and the construction of parts without departing from the spirit of the invention.

40 In the following description and in the claim, parts will be identified by specific names for convenience, but they are intended to be as generic in their application to similar parts as the art will permit.

45 Referring to the drawing and particularly to Figures 1, 2 and 3 and plate 10 comprises part of a switch structure through which the switch control shaft 11 passes. Plate 10 is provided with a pair of oppositely disposed upturned flanges 12 from which one or more sets of switch rotor-stator assemblies can be supported for control by the shaft 11, the rotors being keyed to the shaft. Flanges 12 may be provided, as shown, with small ears 13 for use in mounting or to serve 55 as soldering lugs for attaching a ground connec-

tion to the switch. Plate 10 is also provided with a pair of upturned lugs 14 which are notched on their inner edges to receive the ends of a leaf spring. Shaft 11 is supported for rotation in a bushing 15 which is secured in a central aperture 5 in plate 10. A lock washer 16 fits into a groove in shaft 11 at the end of bushing 15 to prevent longitudinal movement of the shaft in an inward direction.

The inner end of shaft 11 is milled to provide 10 a flat tongue 17, the end 18 of which is made somewhat narrower than the rest.

An indexing disc 19, preferably of metal, is provided with a central aperture having a circular portion and a pair of side notches which are 15 adapted to fit over the tongue 17 of the shaft so that disc 19 rests against the end of the round portion of the shaft. The shoulders on tongue portion 17 may be upset over disc 19 to secure it to the shaft. A washer 20 is disposed between 20 disc 19 and the end of bushing 15 and serves to space disc 19 from plate 10. The edge of disc 19 is formed with an annular series of rounded teeth 21 so as to provide spaced notches 22 between them, corresponding to the desired switch 25 positions.

Indexing spring 23, comprising a narrow leaf spring has a rounded hump 24 at its middle and is bent into resilient U-shaped loops 35 near its ends. The extreme ends are bent back to provide hooked portions 25. The spring is mounted on plate 10 by compressing it between lugs 14 with portions 25 hooked into the notches in lugs 14. Central hump 24 is thereby arranged to press 30 into the notches 22 of disc 19 under pressure of 35 the spring.

It will be seen that this provides an indexing means for determining the stopping positions of the switch. When shaft 11 is turned by a knob or other means mounted on its outer end, whereby 40 the switch contacts are moved into or out of engagement, the spring 23 will ride over the rounded teeth 21 and the hump 24 in the spring will always tend to bring the switch to rest in a position such that the hump 24 presses into one 45 of the notches 22. This may correspond to a closed or an open position of the switch contacts, as desired.

Plate 10 is also provided with a struck-up ear 26 and disc 19 with a pair of downwardly projecting ears 27 which come into engagement with ear 26 at certain switch positions to limit the rotation 50 of the switch.

Figures 4 and 5 show a modified form of shaft mounting which is particularly suitable where 55

several switch sections are to be controlled by the same shaft and index means. According to this arrangement a round shaft 28 is provided with a reduced recessed circular section 29 at its end. Disc 19 fits over the reduced circular section 29 so as to rest against the end of the larger circular part of shaft 28 and a pair of tongues 30 are stripped down from the wall of reduced portion 29 to fit into the two notches in disc 19. A flat shaft 31 having a tapered end 32 may then be wedged into the recess and slots in the end of the round shaft. Shaft 31 passes through the various switch sections and is keyed to the rotor members of each section so as to control the rotation thereof.

It is evident that a switch index mechanism is provided according to the present invention which is simple and economical of construction and fool-proof in operation. Should the index spring 23 become damaged or bent it can readily be replaced without disassembling the entire switch.

While the present invention, as to its objects and advantages, has been described herein as

carried out in specific embodiments thereof, it is not desired to be limited thereby but it is intended to cover the invention broadly within the spirit and scope of the appended claim.

What is claimed is:

An electric switch index mechanism comprising a switch mounting plate, a rotor control shaft passing therethrough, a notched disc mounted on said shaft to rotate therewith, said disc being adjacent said mounting plate, a pair of opposed projections upstanding from said mounting plate beyond the edge of said notched disc, and a replaceable index spring mounted between said projections, said index spring comprising a leaf spring having a central disconformity engaging the edge of said notched disc, the ends of said leaf spring being angularly disposed with respect to the body of said spring and having hooked ends engaging and hooking against the inner sides of said upstanding projections whereby said spring is held in compression between said projections.

KENNARD NEWMAN.
